UNITED STATES PATENT OFFICE.

FRANK W. SCHWINN, OF CHICAGO, ILLINOIS.

STARTER FOR INTERNAL-COMBUSTION ENGINES.

1,215,877.

Specification of Letters Patent. Patented Feb. 13, 1917.

Application filed February 19, 1916. Serial No. 79,256.

To all whom it may concern:

Be it known that I, FRANK W. SCHWINN, a citizen of the United States, residing at Chicago, in the county of Cook and State of Illinois, have invented a new and useful Improvement in Starters for Internal-Combustion Engines, of which the following is a specification.

My invention relates to certain new and useful improvements in starting mechanism for internal-combustion engines. The object of the invention is to provide a simple and efficient combination of mechanisms by which an internal-combustion engine may be cranked for starting the same, the arrangement being such that the initial movement of the cranking mechanism acts to relieve the compression in the engine cylinder, or cylinders, to permit a quick initial acceleration. The invention is particularly adaptable for internal combustion engines of the type used on motorcycles. For the purpose of making the invention more clear, I have illustrated a specific construction of apparatus embodying the same in the accompanying drawings, in which:—

Figure 1 is a side elevation of the central portion of a motorcycle frame, showing an internal combustion engine mounted therein, and connected with my improved starter;

Fig. 2 is an enlarged detailed side elevation of the starter mechanism in inoperative position;

Fig. 3 is a diagrammatic view illustrating the action of the starter;

Fig. 4 is a similar view showing a further advanced position of the starting lever.

Fig. 5 is an enlarged side elevation of the lower portion of the motor, showing its connection with the transmission. Fig. 6 is an enlarged vertical section showing the compression relief mechanism; and Fig. 7 is a section on the line 7 of Fig. 5 and showing the clutch connection between the starting gear and its shaft.

Referring more particularly to the drawings, the numeral 10 designates in general the frame of the motorcycle, the frame shown being of the open type carrying a twin-cylinder internal-combustion engine 11 and a transmission frame 12 at its bottom portion in the relation shown. Within the frame 12 there is adjustably mounted a gear box 13, the adjustment being provided by slots 14 arranged longitudinally of the frame 12 so that the gear box may be moved

toward and away from the motor for the purpose of tightening or loosening the chain which commonly connects these members. This construction is old and well known in the art and I will therefore describe the parts thereof only in so far as they coöperate with my invention.

One of the shaft members 15 of the transmission gearing, preferably the shaft-member which is directly connected with the motor as by the chain 15¹ shown in Fig. 5, is extended out of the gear box 13, and is provided on its extending end with a gear wheel 16. A shaft 17 mounted parallel with the shaft 15 and carried in journals in the gear box 13 has a sector gear 18 arranged in operative relation to the gear 16, so as to mesh with the teeth of the latter and thereby drive the shaft 15 and through it the crank-shaft of the motor. The far end of the shaft 17 (as viewed from Fig. 1), has mounted thereon a lever 19 which may be provided with a folding crank pin or a similar device by which the lever may be actuated by the hand or foot of the operator to rock the shaft, this lever being normally held in the position shown in Fig. 1 by a spring, counter-weight or other device, not shown.

Formed integrally with the hub of the sector gear 18 or otherwise secured to the projecting end of the rock-shaft 17, there is a cam member 20 having a protuberance thereon which is adapted to engage and lift an angular foot carried by a lever 21 journaled upon a stud mounted in the gear-box 13. The lever 21 has a link 22 connected therewith by which the motion of the lever is communicated to a compression relief lever 23 on the internal combustion engine.

As shown in Fig. 6 the compression relief lever 23 has a cam-shaped end 25 which engages a spring-held plunger 26, the conical lower end of which is adapted to be forced between the bell-crank members 27 by which the cam 28 operates the valves of the engine cylinders. By rocking the lever 23 the connections described serve to elevate one valve of each of the two engine cylinders above its seat, whereby the compression is relieved. Since it is designed that the gear-box 13 be moved as a unit toward and away from the engine 11, it is desirable that the link 22 be provided with a turn-buckle 24 therein, by which its length may be altered to conform to the adjustment of the gear-box,

The operation of my improved starter will be best understood from Figs. 2, 3 and 4, in which the relation of the parts for three different positions of the starting lever are shown. From these figures it will be noted that as the shaft 17 is rocked in a counter-clockwise direction the protuberance of the cam 20 will engage the toe or foot member of the lever 21 rocking the latter to the right, as viewed in the drawings, will maintain the lever in its tilted position for a certain predetermined angular movement of the shaft 17, and will then permit the lever to return to its normal position, as the cam protuberance passes out from under its foot. As is clearly shown in Figs. 2, 3 and 4, the opposite faces of the cam protuberance are of equal inclination as are the opposite faces of the lever foot with which these faces co-operate. The mechanism is reversible therefore, that is, the cam may ride beneath the foot to shift the lever 21 when moved in the starting or counter-clockwise direction, indicated by the arrows in Figs. 2, 3 and 4, and also when turning to the normal position shown in Fig. 1.

For the purposes of making clear the advantages of my improved construction I will describe in some detail the procedure employed in starting the engine by my mechanism, though it is believed that the operation of the mechanism will have been made clear from the description of its parts. Assuming that the elements of the mechanism are in the position shown in Fig. 1, and that it is desired to start the engine, force will be applied to the lever 19 as by kicking or pushing the same with the foot in a well-known manner, thereby rocking the shaft 17 in a counter-clockwise direction. It will be noted that in the normal position of the parts, the sector gear 18 is out of engagement with the gear wheel 16, so that the lever 19 may have a certain predetermined free movement before these members engage. This is of advantage in that it permits the rock-shaft 17 and its connected parts, as well as the foot of the operator, to gain considerable momentum before any resisting force is interposed. During this first free movement of the shaft 17, the lever 21 will have been oscillated, moving it from the position shown in Figs. 1 or 2, to the position shown in Fig. 3, thereby actuating the compression relief devices of the motor through the lever 23 thereon. Approximately at the time that the compression relief devices have reached their operative position, the end of the sector gear 18 engages the gear-wheel 16, and due to the momentum of the parts and the fact that the compression resistance of the engine has been relieved, the motor crank-shaft will be started with a quick jerk. The cam protuberance is preferably formed to provide a short

dwell for holding the compression relief devices in operative position through some further angular movement of the rock shaft, during which time the crank shaft of the motor will have been accelerated to a relatively high velocity. Upon further movement of the rock shaft the cam protuberance passes out from under the foot of the lever 21, permitting the compression relief devices (which will be spring returned according to the ordinary practice) to come to the inoperative position. The remainder of the stroke of the starting lever 19 will then crank the motor against the resistance of the compression of its cylinders, but since the motor crank-shaft and its fly wheels have already acquired considerable momentum, this cranking under compression is carried out with the minimum amount of exertion. If the engine is in normal condition an explosion or explosions will occur therein during the intermediate or later portion of the stroke of the starting lever 19. By reason of the fact that such explosion or explosions occur under normal compression instead of under reduced compression, sufficient power will be developed ordinarily to start the motor in normal operation. It will be understood that the gear wheel 16 is provided with an overrunning clutch of the usual form, such, for instance, as the ratchet-toothed clutch shown at 16¹ in Fig. 7, whereby, when the motor has been started, the gear wheel 16 will stop and may then rotate in the reverse direction as the starting lever and its connected sector gear are returned to the normal position, as shown in Figs. 1 and 2. During such return movement it is clear that the cam will again lift the foot of the lever 21 to throw the compression relief devices into operation, but this movement will be of such short duration as to have no appreciable effect upon the operation of the motor.

In the foregoing I have described in considerable detail one specific embodiment of the invention, and have pointed out the method of operation and advantages obtainable by this construction. It is to be understood, however, that the description referred to is illustrative only, and for the purpose of making the invention more clear, and that it is not to be regarded as a limitation of the scope of the invention, except in so far as such limitation appears within the terms of the following claims, in which it is my intention to claim all novelty inherent in my invention as broadly as is permissible in view of the prior art.

What I claim as new and desire to secure by Letters Patent is:

1. The combination with an internal combustion engine having means for relieving the compression in the cylinders thereof, of a means for driving the crank shaft of

- the engine in a forward direction for starting the said engine, and connections between said starting means and the compression relief mechanism for throwing the latter to 5 operative position by initial movement of the former, and for permitting the compression relief mechanism to return to inoperative position during further operative movement of the starting means.
- 10 2. In combination with an internal combustion engine having means for relieving the compression in the cylinders thereof, of a starting shaft for mechanically applying power to said engine for starting the same, 40 means for driving said shaft, a cam carried by said shaft, and a cam-follower operatively related to said cam and having connections with said compression relieving means.
- 15 3. The combination with an internal combustion engine having means for relieving the compression in the cylinders thereof, of a rock-shaft adapted to be mechanically connected with the said engine for starting the same, a cam carried by the said rock-shaft, 45 a follower mounted in operative relation to the cam, and connections between the said cam-follower and compression relief means, the parts being arranged to relieve the compression of the engine during the initial part 50 only of the operative movement of the said rock-shaft.
- 20 4. The combination with an internal combustion engine having means for relieving the compression in the cylinder thereof, of a shaft connected with the said engine and having a gear thereon, a rock-shaft mounted parallel with said first-named shaft having a sector gear thereon adapted to be moved into and out of engagement with said first-named gear, a lever for applying power to 55 said rock-shaft, a cam carried by said rock-shaft, a follower for said cam, connections between said follower and the said compression relief means, the parts being so arranged that the said compression relief means is actuated during the initial part only of the operative movement of said rock-shaft.
- 25 5. The combination with an internal combustion engine having means for relieving the compression in the cylinder thereof, of a shaft connected with the said engine and having a gear thereon, a rock-shaft mounted 60 parallel with said first-named shaft having a sector-gear thereon adapted to be moved into and out of engagement with said first-named gear, a lever for applying power to said rock-shaft, a cam carried by said rock-shaft, a follower for said cam, and connections between said follower and the said compression relief means for operating the latter by movement of said rock-shaft.

FRANK W. SCHWINN.
